UNITED STATES PATENT OFFICE.

CHARLES E. GAMBILL, OF OAK PARK, ILLINOIS.

DESIGN FOR A COMBINED MOTOR AND SWITCHBOARD FRAME.

54,253.

Specification for Design.

Patented Dec. 9, 1919.

Application filed March 24, 1919. Serial No. 284,872. Term of patent 3½ years.

To all whom it may concern:

Be it known that I, CHARLES E. GAMBILL, a citizen of the United States, residing at Oak Park, county of Cook, and State of Illinois, have invented a new, original, and ornamental Design for a Combined Motor and Switchboard Frame, of which the following is a specification, reference being had to the accompanying drawing, forming a part hereof, in which—

Figure 1 is a front perspective view of a combined motor and switchboard frame in accordance with the design; and Fig. 2, a rear perspective view of the same.

I claim:

The ornamental design for a combined motor and switchboard frame, as shown.

CHARLES E. GAMBILL.
